UNITED STATES PATENT OFFICE.

WILLIAM ROSS, OF MONTREAL, CANADA.

ACETYLENE-GAS GENERATOR.

SPECIFICATION forming part of Letters Patent No. 645,271, dated March 13, 1900.

Application filed July 11, 1893. Serial No. 685,653. (No model.)

To all whom it may concern:

Be it known that I, WILLIAM ROSS, of the city of Montreal, Province of Quebec, Canada, have invented certain new and useful Improvements in Gas Apparatus; and I do hereby declare that the following is a full, clear, and exact description of the same.

My invention relates particularly to the manufacture of acetylene gas; and it has for its object to supply absolutely-pure gas to the consumer, to enable all the air that may happen to gather in the apparatus to be exhausted before any gas can flow, to provide an automatic feed of the calcium carbid as the gas-generative power of the supply in the apparatus diminishes, to provide a gas-holder that will be capable of containing a comparatively-large supply of gas, thus necessitating a long seal, and at the same time enable the gas when generated to pass through and free itself only from that amount of water necessary to its generation, to provide an apparatus that may be carried from place to place without any danger of its parts becoming disarranged, and to further improve the general construction of this class of apparatus, as will be hereinafter clearly set forth.

The invention may be said briefly to consist of a body portion in the form of a cylinder having its lower end closed by a double bottom formed of a pair of cones connected together and to the lower end of the cylinder at their bases, each cone being truncated and the inner one connected at its apex to the lower end of a pipe which extends to a point on a level with the upper end of the cylinder. Over this pipe is fitted a core in the form of a cylindrical drum, having a longitudinal central opening of greater diameter than said pipe in order to allow it to take over said pipe and leave an encircling space, while an opening is cut through the cylinder and inner cone at their adjoining edges, and the edges of said openings are connected by a diaphragm, thus maintaining the division between the space in the cylinder and the space between the two cones and providing a passage for a carbid-drawer, to be presently described. A lateral chamber is formed on the exterior of the cylinder and has an inclined bottom extending on a similar plane to that of the outer or lowermost cone and has an opening correspond-

ing to the said passage and receives a drawer having its forward end inclined and formed of wire-mesh and adapted to be slipped into the space inclosed by said cones and said inclined end cover over the truncated apex of said lower cone, to which a draw-off cock is connected. A vertically-movable dome is arranged within said cylindrical body portion, which is filled to almost its full capacity with water. The gas-exhaust pipe leads from a point within the dome above the level of the water downwardly and through the water and to the consumer. This pipe is adapted to receive only the pure gas from the dome by means of a float resting on the surface of said water and presenting a space between it and the surface, with which space said pipe is connected by a flexible connection. A safety blow-off pipe is provided by taking a stand-pipe from the space in the dome to the external chamber before mentioned, from which a second pipe leads to the open air, the stand-pipe having its upper end furnished with a safety-valve adapted to be operated by the dome when it has been raised by the gas-pressure to any predetermined height, the gas being thereby allowed to escape to the open air and the pressure in the dome reduced.

The means that I prefer to use for automatically supplying the calcium carbid to the space between the cones (which space is filled with water through the drawer-passage before the drawer is slid in) consists of an endless belt carrying a series of buckets to which the calcium carbid is fed either from a hopper or, as I prefer, by hand, the belt being actuated by means of a star-wheel mounted upon one of the shafts of the pulleys over which the belt is looped, said star-wheel being acted upon by the dome through a projection from the exterior of the dome and revolved sufficiently to cause one of the buckets to drop its contents into the drawer.

For full comprehension, however, of the foregoing and of my invention in its entirety reference must be had to the accompanying drawings, forming a part of this specification, in which like symbols indicate the same parts, and wherein—

Figure 1 is a side elevation of an apparatus constructed according to my invention; Fig. 2, a longitudinal vertical sectional view thereof;

taken on line 22, Fig. 1; Fig. 3, a transverse horizontal sectional view thereof looking down, taken on line 33, Fig. 2; Fig. 4, a detail view of the star-wheel through the medium 5 of which the belt is driven; Fig. 5, a detail view of the endless belt; Fig. 6, a detail plan view of the under side of the float; Fig. 7, an enlarged transverse horizontal sectional view taken on line 77, Fig. 2; and Fig. 8, a detail 10 view of the safety-valve.

10 is the cylindrical body portion, having a pair of oppositely-arranged truncated cones 11 and 12, connected at their bases to the bottom edge thereof, thus forming the generating 15 or decomposing chamber 9. Openings are cut through the cylindrical body portion and the upper cone 11, and the edges of said openings are connected by a diaphragm 13, thus forming a passage 14. A chamber 15 is 20 formed on the exterior of the body portion and has an opening corresponding to the before-mentioned openings cut in its side to receive a drawer 16, adapted to slide into the passage 14, said drawer having its inner end 25 17 formed of wire-mesh or the like adapted to act as a false bottom to the generating or decomposing chamber 9, the truncated lower end of which has a drain-cock 18 connected thereto. This drawer carries the calcium 30 carbid, and the passage 14 serves as a port through which the chamber 9 can be supplied with water.

20 is the gas-conducting pipe, which leads from the truncated apex of the cone 11, to 35 which it is connected, to a point on a level with the upper end of the cylindrical body portion.

21 is the dome or gas-holder, about equal in length to and slightly less in diameter than 40 the cylindrical body portion within which it is located, a water seal 22 serving to retain the gas fed to the interior thereof.

It is a well-known fact that acetylene gas is much more buoyant than air and also that 45 the greatest difficulty has been experienced in trying to prevent the collection of air in the gas-chamber. I completely overcome this difficulty by causing the first flow from the gas-chamber to be whatever air may have collected therein, and this I accomplish by means 50 adapted to automatically adjust itself to always draw from the lowermost point of the gas-chamber. To this end I provide a float 55 adapted to rest upon the surface of the water seal 22, which constitutes the bottom of the gas-chamber X, and this float constantly suspends the lower end of the flow-pipe a short distance above said water seal. This float 60 consists of a plate 25, having a series of preferably three air-chambers formed on its under side by means of dish-like devices 26, soldered or otherwise connected thereto, said plate being slotted, as at 27, to accommodate the gas-conductor 20, and perforated, as at 65 28, so as to provide an opening from the gas-chamber to the lower end of a short stand-pipe 29, connected to the edge of such per-

foration 28. The main length 30 of the flow-pipe extends from a point within the gas-chamber downwardly through the seal and 70 out of the body portion of the apparatus, as at 31, the upper end of this length 30 being connected to the short stand-pipe 29 by an intermediate length of pipe 31^a, connected to each by any well-known and approved form of 75 universal joints, (indicated at 32,) thus enabling the float to fall and rise with the seal as it evaporates and is replenished and at the same time to cause the gas to be drawn 80 constantly from the lowermost point in the gas-chamber.

33 is the safety blow-off pipe, which leads from a point above the water-level in the gas-chamber downward around the lower edge of the dome 21 when in its lowermost 85 position and upwardly between said dome and the cylindrical body portion 10 to a point above the uppermost position attainable by the lower edge of said dome. This pipe has its outer end sealed and communicates with 90 the exterior carbide-chamber 15 through an opening cut through the wall of the casing, as shown in Fig. 7, a short distance below the top of said chamber 15, which communicates with the open air through a pipe 34. My 95 object in extending the pipe 33 is to obviate any chance of the lower edge of the dome tripping upon the upper end thereof descending. The end of the pipe 33 within the dome is furnished with a safety-valve 35, operated 100 by a stop 36, carried on the inside of the dome and adapted to open the valve when the dome rises, owing to excessive gas-pressure, to a predetermined height, thus allowing the gas to blow off through a pipe 34, connecting the upper end of the chamber 15 with the open air and the pressure to be reduced 105 to normal.

In order to enable the apparatus to automatically feed itself with carbide, a horizontal 110 chamber 37 is provided and mounted upon the exterior of the cylindrical body portion adjacent to the chamber 15, with which it communicates by means of a chute 38, the lower end whereof is normally closed by a 115 spring-door 39. An endless belt 40, provided with a series of buckets 41, is located within said chamber 37 and takes over a pair of pulleys 42 and 43, mounted upon shafts 44 and 45, respectively, bearing in the sides of said 120 chamber 37. A star-wheel 46, mounted upon the shaft 44, is adapted to be actuated by a bracket projection upon the dome as it descends, thus causing the belt to travel a sufficient distance to upset one of the buckets 125 and discharge the calcium carbide contained therein into the chute 38, the door 39 of which will be opened by the weight of the carbide, which will pass through it and be precipitated 130 into the drawer, down which it will slide into the generating or decomposing chamber and rest upon the wire-mesh end of said drawer in order that it may be readily withdrawn for 135 cleansing purposes, while the dead-water may

be as readily drawn off through the cock 18 at the bottom of the apparatus.

I have found that the large mass of water necessitated by a construction according to the foregoing not only interferes exceedingly with the portability of the apparatus, but also necessitates that the apparatus be constructed of exceedingly strong and heavy material. In order to obviate this defect, I provide a core in the form of a hollow cylindrical drum 50, having a longitudinal central opening 51 of sufficiently-greater diameter than the conductor 20 to take over it and provide a free space therebetween and the sides of said opening, said core being supported upon legs 52, connected at their bottom ends to the upper side of the cone 11. This core serves the double purpose of displacing an unrequired mass of water, and with it an undesirable weight, and of enabling the gas to be cooled, this latter being effected by passing both the conductor 20 and the main portion 30 of the flow-pipe through the body of water in the gas-holder, which, as has been clearly set forth, is divided from the body of water in the decomposing-chamber and is therefore not subject to the heat induced by the decomposition of the carbid.

What I claim is as follows:

1. An acetylene-gas apparatus comprising a generating-chamber containing water and consisting of a pair of truncated cones located one above the other and connected together and hermetically sealed at their bases; a lateral passage through which calcium carbid can be supplied to the water in said chamber; a gas-conducting pipe connected at one end to the truncated apex of the upper cone; and means for discharging the contents of the lower cone, for the purpose set forth.

2. An acetylene-gas apparatus comprising a generating-chamber containing water and consisting of a pair of truncated cones located one above the other and connected together and hermetically sealed at their bases; means comprising an inclined lateral conducting passage and a horizontally-arranged traveling belt adapted to conduct predetermined quantities of calcium carbid to said conducting-passage, for supplying calcium carbid to the water in said chamber; a gas-conducting pipe connected at one end to the truncated apex of said upper cone; and means for discharging the contents of said lower cone, for the purpose set forth.

3. An acetylene-gas apparatus comprising a cylindrical body portion, a generating-chamber consisting of a pair of truncated cones connected together, and to the lower end of said body portion at their bases and constructed to contain a body of water; means for supplying calcium carbid to the water in said generating-chamber; a dome of less diameter than and taking into said cylindrical body portion; a water seal in said body portion and sealing the lower end of said dome; a gas-conducting pipe connected at its lower

end to the truncated apex of said inner cone and leading through said seal to a point above the surface thereof; a gas-flow pipe leading 70 from a point above the water seal in the dome downwardly through said seal and out of the body portion; and a draw-off cock connected to the truncated apex of the outer cone, substantially as and for the purpose set forth. 75

4. An acetylene-gas apparatus comprising a cylindrical body portion, a generating-chamber consisting of a pair of truncated cones connected together, and to the lower end of said body portion at their bases; and constructed 80 to contain a body of water; means comprising a horizontally-arranged traveling belt, having a series of partitions projecting at right angles thereto, and a conducting-passage for supplying calcium carbid to the water 85 in said generating-chamber; a dome of less diameter than and taking into said cylindrical body portion; a water seal in said body portion and sealing the lower end of said dome; a gas-conducting pipe connected at its 90 lower end to the truncated apex of said inner cone and leading through said seal to a point above the surface thereof; a gas-flow pipe leading from a point above the water seal in the dome downwardly through said seal and 95 out of the body portion; and a draw-off cock connected to the truncated apex of the outer cone, substantially as and for the purpose set forth.

5. An acetylene-gas apparatus comprising 100 a generating-chamber, a removable perforated diaphragm extending transversely of said chamber a short distance above the bottom thereof for supporting the calcium carbid, a lateral inclined opening or passage to said 105 chamber and means for removing said perforated diaphragm through such lateral opening substantially as described.

6. In an acetylene-gas apparatus comprising a generating-chamber, having a lateral 110 inclined opening or passage, a drawer for containing calcium carbid and adapted to be slid into said chamber through said passage; means for sealing the opening through which said drawer slides and said drawer having its 115 inner end formed of wire mesh and arranged at an angle to the vertical, substantially as and for the purpose set forth.

7. An acetylene-gas apparatus comprising 120 a cylindrical body portion, a pair of truncated cones connected together, and to the lower end of said body portion, at their bases; registering openings cut through said body portion and the inner cone, the edges of said openings being connected by a diaphragm; 125 a drawer adapted to be slid into the passage formed by said openings and diaphragm; a dome of less diameter than and taking into said cylindrical body portion; a water seal in said body portion and sealing the lower end 130 of said dome; a gas-conducting pipe connected at its lower end to the truncated apex of said inner cone and leading through said seal to a point above the surface thereof; a gas-

flow pipe leading from a point above the water seal in the dome downwardly through said seal and out of the body portion; and a draw-off cock connected to the truncated apex of the outer cone, for the purpose set forth.

8. An acetylene-gas apparatus comprising a cylindrical body portion, a pair of truncated cones connected together, and to the lower end of said body portion, at their bases; registering openings cut through said body portion and the inner cone, the edges of said openings being connected by a diaphragm; a drawer adapted to be slid into the passage formed by said openings and diaphragm, said drawer having its inner end formed of wire mesh or the like; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a gas-flow pipe leading from a point above the water seal in the dome downwardly through said seal and out of the body portion; and a draw-off cock connected to the truncated apex of the outer cone, for the purpose set forth.

9. An acetylene-gas apparatus comprising a cylindrical body portion, a pair of truncated cones connected together, and to the lower end of said body portion, at their bases; registering openings cut through said body portion and the inner cone, the edges of said openings being connected by a diaphragm; a drawer adapted to be slid into the passage formed by said openings and diaphragm; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a gas-flow pipe leading from a point above the water seal in the dome downwardly through said seal and out of the body portion; a float resting upon the surface of said seal, a short stand-pipe carried by said float and having its lower end maintained thereby constantly a short distance above the surface of said seal, a flexible tubular connection between the upper ends of said stand-pipe and flow-pipe; and a draw-off cock connected to the truncated apex of the outer cone, for the purpose set forth.

10. An acetylene-gas apparatus comprising a cylindrical body portion, a pair of truncated cones connected together and to the lower end of said body portion, at their bases; registering openings cut through said body portion and the inner cone, the edges of said openings being connected by a diaphragm; a drawer adapted to be slid into the passage formed by said openings and diaphragm; a dome of less diameter than and taking into said cylindrical body portion; a water seal in

said body portion and sealing the lower end of said dome; a gas-conducting pipe connected at its lower end to the truncated apex of said inner cone and leading through said seal to a point above the surface thereof; a core located in said cylindrical body portion and consisting of a cylindrical drum having a longitudinal opening therethrough of slightly-greater diameter than and adapted to take over said gas-conducting pipe, means for supporting said core a short distance above the inner cone; a gas-flow pipe leading from a point above the water seal in the dome downwardly through said seal and out of the body portion; and a draw-off cock connected to the truncated apex of the outer cone, for the purpose set forth.

11. An acetylene-gas apparatus comprising a cylindrical body portion, a pair of truncated cones connected together and to the lower end of said body portion, at their bases; registering openings cut through said body portion and the inner cone, the edges of said openings being connected by a diaphragm; a drawer adapted to be slid into the passage formed by said openings and diaphragm, said drawer having its inner end formed of wire mesh or the like; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a core located in said cylindrical body portion and consisting of a cylindrical drum having a longitudinal opening therethrough of slightly-greater diameter than and adapted to take over said gas-conducting pipe, means for supporting said core a short distance above the inner cone; a gas-flow pipe leading from a point above the water seal in the dome downwardly through said seal and out of the body portion; and a draw-off cock connected to the truncated apex of the outer cone, for the purpose set forth.

12. An acetylene-gas apparatus comprising a cylindrical body portion, a pair of truncated cones connected together, and to the lower end of said body portion, at their bases; registering openings cut through said body portion and the inner cone, the edges of said openings being connected by a diaphragm; a drawer adapted to be slid into the passage formed by said openings and diaphragm, said drawer having its inner end formed of wire mesh or the like; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a gas-flow pipe leading from a point above the water seal in the dome downwardly through said seal and out of the body portion; a float resting upon the surface of said seal,

a short stand-pipe carried by said float and having its lower end maintained thereby constantly a short distance above the surface of said seal, a flexible tubular connection between the upper ends of said stand-pipe and flow-pipe; and a draw-off cock connected to the truncated apex of the outer cone, for the purpose set forth.

13. An acetylene-gas apparatus comprising a cylindrical body portion, a pair of truncated cones connected together and to the lower end of said body portion, at their bases; registering openings cut through said body portion and the inner cone, the edges of said openings being connected by a diaphragm; a drawer adapted to be slid into the passage formed by said openings and diaphragm, said drawer having its inner end formed of wire mesh or the like; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a core located in said cylindrical body portion and consisting of a cylindrical drum having a longitudinal opening therethrough of slightly-greater diameter than and adapted to take over said gas-conducting pipe; means for supporting said core a short distance above the inner cone; a gas-flow pipe leading from a point above the water seal in the dome downwardly through said seal and out of the body portion; a float resting upon the surface of said seal, a short stand-pipe carried by said float and having its lower end maintained thereby constantly a short distance above the surface of said seal, a flexible tubular connection between the upper ends of said stand-pipe and flow-pipe, and a draw-off cock connected to the truncated apex of the outer cone, for the purpose set forth.

14. An acetylene-gas apparatus comprising a cylindrical body portion, a pair of truncated cones connected together and to the lower end of said body portion, at their bases; registering openings cut through said body portion and the inner cone, the edges of said openings being connected by a diaphragm; a drawer adapted to be slid into the passage formed by said openings and diaphragm, said drawer having its inner end formed of wire mesh or the like; a dome of less diameter than and taking into said cylindrical body portion; a water seal in said body portion and sealing the lower end of said dome; a gas-conducting pipe connected at its lower end to the truncated apex of said inner cone and leading through said seal to a point above the surface thereof; a core located in said cylindrical body portion and consisting of a cylindrical drum having a longitudinal opening therethrough of slightly-greater diameter than and adapted to take over said gas-conducting pipe; means for supporting said core a short distance above the inner cone; a gas-flow pipe leading from a point above the water seal in the dome downwardly through said seal and out of the body portion; a float resting upon the surface of said seal, a short stand-pipe carried by said float and having its lower end maintained thereby constantly a short distance above the surface of said seal, a flexible tubular connection between the upper ends of said stand-pipe and flow-pipe; and a draw-off cock connected to the truncated apex of the outer cone, for the purpose set forth.

In testimony whereof I have affixed my signature in presence of two witnesses.

WILLIAM ROSS.
